UNITED STATES PATENT OFFICE.

ROMOLO NARDI, OF CAMDEN, NEW JERSEY.

MAGAZINE PENCIL.

Application filed December 9, 1924. Serial No. 754,736.

To all whom it may concern:

Be it known that I, ROMOLO NARDI, a citizen of the United States, residing at Camden, in the county of Camden and State of New Jersey, have invented new and useful Improvements in a Magazine Pencil, of which the following is a specification.

My invention relates to new and useful improvements in a magazine pencil, the primary object of which is to provide in a device of this character means for expelling or propelling the lead in that magazine which is in operative position.

Another object of the invention is to so construct the means which causes any one of the magazines to be projected into operative position that said means may be used for propelling the lead to expel or project said lead from its magazine.

20 A further object of the invention is to provide a magazine pencil unit which will be compact and easily assembled in a pencil casing.

A still further object of the invention is to provide means for repelling the magazines and also provide means for forcing the pencil casing elements outward or in opposite directions to each other.

With these ends in view, this invention 30 consists in the details of construction and combination of elements hereinafter set forth and then specifically designated by the claims.

In order that those skilled in the art to 35 which this invention appertains, may understand how to make and use the same, I will describe its construction in detail, referring by numerals to the accompanying drawings forming a part of this application, in 40 which:

Fig. 1, is a side elevation of a pencil embodying my invention with the parts illustrated in the positions assumed when the pencil is not in use.

45 Fig. 2, is a longitudinal sectional view thereof with the parts positioned as when the pencil is in use with one of the magazines projected into an operative position.

Fig. 3, is an enlarged fragmentary sectional view of the upper portion of the pencil.

Fig. 4, is a section at the line 4—4 of Fig. 3.

50 Fig. 5, is a view similar to Fig. 3 of that portion of the pencil below the part shown in Fig. 3.

Fig. 6, is a section at the line 6—6 of Fig. 3.

Fig. 7, is a fragmentary detail sectional side elevation of one of the lead magazines 60 and associated parts.

Fig. 8, is an end view of the lead propelling rod.

Fig. 9, is a fragmentary sectional elevation thereof.

Fig. 10, is a fragmentary sectional elevation of the upper portion of the pencil showing the manner in which the pencil casing members may be normally forced apart.

Fig. 11, is an enlarged perspective view 70 of the magazine unit.

In carrying out my invention as here embodied, 2 represents the lower pencil casing having its outer end fashioned into cone shape to provide a restricted opening or 75 outlet 3 and enlarged at its inner end to provide a shoulder 4 and a seat 5 while adjacent said inner end are produced a plurality of longitudinal ribs 6 preferably formed from the metal of the casing and projecting 80 beyond the outer surface of said casing.

This lower casing is telescopically mounted in the upper casing 7 which has a restricted area or portion of smaller diameter at its inner end as indicated at 8 and in 85 this restricted portion are formed a plurality of guideways 9, said guideways being equal in number to the ribs 6 and said guideways and ribs must be evenly and regularly positioned so that all of the ribs will pass 90 into the guideways when any one of said ribs is moved into alignment with any one of the guideways. The guideways and ribs are preferably three in number and each one of them represents the color of a lead held 95 in the pencil, as for instance, black, red and blue and each of the ribs has the name of its lead delineated adjacent thereto on the lower casing as shown at 10.

The lower casing 2 besides telescoping in 100 the upper casing 7 will rotate therein and therefore with each guideway 9 is associated an offset 11 so that when the ribs will pass through the guideways 9 and one casing member rotated relative to the other 105 an end of each rib will engage the offset portion 11 and the two casings be held in a retracted position, as plainly shown in Fig. 2.

A cap 12 is mounted on the outer end 110 of the upper casing member and in its axial center is journaled a short shaft 13 having

a button or operating means 14 fixed to its outer end while a small spur gear 15 is fixed to its inner end and the latter meshes with another spur gear 16 fixed to the ejector 17 also journalled in the cap 12 parallel with the shaft 13.

In the lower casing is mounted the unit shown in Fig. 11 and includes a ring 18 fixed in the seat 5 at the inner end of the lower casing, said ring carrying a plurality of hangers or stirrups 19 having inturned lower ends 20 projecting through suitable longitudinal slots 21 in the lead magazines 22 each having a piece of lead 23 therein, said lead being retained by friction. Between the inturned end of a hanger or stirrup within a lead magazine and the inner or upper closed end of said magazine is located a coiled spring 24 so that the action of said spring normally forces the magazine inward or upward.

At the inner or upper end of each magazine is a yoke 25 through which passes the lead propelling rod 26 and said yoke is positioned between the collar 27 and sleeve 28 fixed in spaced relation upon the lead propelling rod whereby the latter may revolve in the yoke although the two will slide or move together longitudinally. The sleeve 28 has a socket 29 formed at its upper end which socket is of some polygonal shape, as for instance a slot, a triangle or any other desirable formation to receive the end of the ejector 17 which is similarly shaped and if found desirable the socket and an end of the ejector may be beveled in order to guide the ejector into the socket and permit a certain amount of freedom of movement relative to each other.

40 The lead propelling rod 26 is threaded as at 30 throughout the major portion thereof for threaded connection with the coupler 31 projecting into a magazine through the lead pusher or propeller 33 located within the magazine and engaging the inner end of a lead.

From the foregoing description it will be seen that when it is desired to use a particular lead the casing members 2 and 7 are rotated relative to each other until a rib 6 with which is associated the designation representing the lead desired is in line with a particular one of the guideways 9, said particular guideway being indicated 55 by some suitable mark, as for instance a star 34, Fig. 1. These will have aligned the socket magazine carrying the desired lead with the ejector 17 so that when the lower casing member 2 is moved inward 60 the magazine associated with the socket engaged by the ejector will be held stationary and therefore said magazine will assume an operative position with its lead projecting through the opening 3 in the 65 lower or outer end of the casing 2, as shown

in Fig. 2. Then by giving the two casing members a slight rotation relative to each other the ribs 6 will engage their respective offsets 11 and the two casing members will be held in operative positions.

As all the parts are merely hung on each other the rotation of a casing member relative to another will cause the selected lead magazine to assume an angle without breaking or being otherwise damaged.

When the parts are in operative positions, as shown in Fig. 3, should the lead in use break it may be propelled outward or expelled by revolving the button 14 to transmit motion through the shaft 13, gears 15 and 16, the ejector 17 to the threaded propelling rod 26 the revolving of which will cause the coupler 31 to travel and move the pusher 33 outward thus expelling or propelling the lead until the desired amount is exposed.

When the casing members are collapsed so as to move the parts in an operative position the spring in the barrel associated with the socket engaged by the ejector will be compressed between the outer end of said magazine and the inturned end 20 of its associated hanger or stirrup 19 and therefore when one casing member is rotated relative to the other to disengage a rib from its offset 11 and re-align the ribs with the guideways 9 said spring will tend to return the parts to their normal positions and since the stirrup is carried by the ring 18 and said ring fixed to the lower casing member the latter will be forced outward relative to the upper casing so as to return the two casing members to the positions shown in Fig. 1.

As the springs 24 are naturally very light due to their relative small size it is desirable, in some cases, to provide an additional means for forcing the casing members apart and utilizing the spring 24 merely to keep the magazines under tension and preventing them from falling. To illustrate such an arrangement I have shown a spring 35 within the upper casing member bearing against the inner end of the lower casing member and the cap 12, Fig. 10. The operation of this form of the invention is identical with that previously described and is only an additional means to assist the springs 24.

Of course I do not wish to be limited to the exact details of construction as herein shown as these may be varied within the limits of the appended claims without departing from the spirit of my invention.

Having thus fully described my invention, what I claim as new and useful is:

1. A magazine pencil including telescoping casing members, a plurality of magazines carried by one of said casing members and slidable relative thereto, an ejector

- carried by the other casing member, means associated with each magazine for coaction with the ejector, and means within each magazine associated with the first named 5 means whereby rotation of the ejector will propel a lead from a magazine.
2. A pencil including a collapsible casing, a plurality of magazines, leads in said magazines, means to selectively project the 10 magazines into operative positions, and means for propelling the lead in the selected magazine.
3. A pencil including two casing members, one telescopically mounted in the other, a plurality of lead holders supported by one of the casing members, lead propelling devices in each lead holder, means to actuate said propelling devices, and means to selectively project the lead holders into operative 15 positions and operate the actuating means of the lead propelling devices.
4. A pencil including two casing members, one telescopically mounted in the other, a ring supported by one of the casing members, hangers depending from said ring, each of the hangers having an in-turned foot, a plurality of lead holders located within the ring, each of said lead 20 holders having two longitudinal slots, one of the slots of each lead holder receiving the inturned foot of a hanger, a spring 25 within each lead holder and engaging the inner end of the lead holder and the in-turned foot of its respective hanger to normally force the lead holders inward, a lead propeller within each lead holder, a coupler 30 on the lead propeller and projecting through the other slot in the lead holder, a lead propelling rod having threaded connection with the coupler, means to connect the threaded lead propelling rod with a lead holder 35 whereby the two will move in unison longitudinally while permitting the lead propelling rod to be rotated, a cap on the outer end of the other casing member, an ejector journalled in said cap and adapted to interlock with the ends of the several lead propelling rods whereby a selected lead holder 40 will be projected into an operative position, and means to impart a rotary motion to the ejector whereby the lead propelling rod will be rotated in order to move the lead propellers within the lead holders.

In testimony whereof, I have hereunto affixed my signature.

ROMOLO NARDI.
